HOUSE

Archie B. Swank, Gerald C. Schroeder, and Herbert G. Hammar, Dallas, Tex., assignors to Redman Industries, Inc., Dallas, Tex., a corporation of Delaware

Filed Feb. 27, 1967, Ser. No. 5,963

Term of patent 14 years

(Cl. D13—1)

Fig. 1

Fig. 2

FIG. 3

The dominant features of our design reside in the portions shown in solid lines.

We claim:

The ornamental design for a house, substantially as shown and described.
